UNITED STATES PATENT OFFICE.

ALDEN E. OSBORN, OF NEW YORK, N. Y.

INTERNAL-COMBUSTION ENGINE.

1,216,721.

Specification of Letters Patent. Patented Feb. 20, 1917.

Application filed September 10, 1915. Serial No. 49,912.

To all whom it may concern:

Be it known that I, ALDEN E. OSBORN, a citizen of the United States of America, and a resident of New York, county and State of New York, have invented certain new and useful Improvements in Internal-Combustion Engines, of which the following is a specification, reference being had to the accompanying drawings, forming a part thereof.

10 My invention relates to internal combustion engines, and particularly to such as comprise two cylinders or two groups of cylinders set at an angle to each other.

15 One object of my invention is to provide in an engine of this character, a relatively simple and inexpensive valve mechanism and operating means therefor.

20 Another object is to provide an engine commonly known as an engine of the V-type with valve mechanism which is so arranged and positioned relative to the cylinders, that a single valve crank shaft to which all of the valves are connected may be employed.

25 Other objects and advantages of my invention will be set forth hereinafter, and in order that my invention may be thoroughly understood, I will now proceed to describe the same in the following specification and then point out the novel features thereof in appended claims.

Referring to the drawings:

Figure 1 is a transverse sectional elevation through one pair of cylinders and their valves, of an engine arranged and constructed in accordance with my invention.

30 A series of diagrammatic views are shown in Figs. 2 to 9 inclusive which illustrate the operation of the engine, by showing the pistons and valves and the main and valve crank shafts in different positions.

35 While I have shown only one pair of cylinders, the engine may obviously comprise two groups of cylinders, each group containing two or more cylinders.

40 The structure illustrated in Fig. 1 comprises a pair of cylinders 10 and 11, having their center lines substantially in the same plane but at an angle to each other. They 45 may, for example, be at an angle of 90 degrees. Operating in the cylinders are pistons 12 and 13 which are connected by piston rods 14 and 15 to a wrist pin 16 on the crank shaft 17.

45 Above the crank shaft 17 and between the cylinders 10 and 11 is a valve crank shaft

18 having a wrist pin 19 to which the piston valves 20 and 21 are operatively connected. These valves respectively operate in valve cylinders 22 and 23. The valve cylinder 22 opens at one end into the combustion chamber 24 of the cylinder 10 and the valve cylinder 23 opens into the combustion chamber 25 of the cylinder 11.

50 The construction of the valve cylinders 65 and the location of the admission and exhaust ports forms no part of my present invention and each cylinder, with its valve, may, for example, correspond in construction to the engine shown and described in 70 my copending application Serial No. 879,589, filed December 29, 1914, except that the valve cylinder is at an angle to the engine cylinder. A brief description will therefore suffice.

55 The valve cylinders 20 and 21 are similar to each other and only one will be described. For example, the valve cylinder 20 is provided with a transverse port 26 which is adapted to register with an admission port 27 and with a passage 28 which opens into the engine cylinder 10 at an intermediate point in the stroke of the piston 12. The admission of fuel to the engine is therefore governed by the piston valve in coöperation 85 with the engine cylinder.

60 An exhaust port 29 is adapted to be opened into the combustion chamber 24 when the piston valve occupies its extreme position.

65 The engine and valve cylinders and the combustion chamber are provided with a water jacket 30 in the usual manner.

70 The valve and engine ports in the cylinders 11 and 23 and in the piston valve 21 are designated by corresponding reference numerals except that "a" is suffixed to each.

75 The crank shaft 17 is operatively connected to the valve crank shaft 18, by suitable gearing such as 33, as clearly shown in 100 broken lines in Fig. 1.

80 The operation of the engine will be clearly understood by referring to the diagram shown in Figs. 2 to 9 inclusive.

85 Fig. 2 shows the piston at the left starting on the power stroke and the piston on the right at an intermediate point in the exhaust stroke.

90 Fig. 3 shows the piston on the left at an intermediate point in the power stroke and the piston on the right starting on the suction stroke.

In Fig. 4 the piston on the left is shown at the end of the power stroke starting on the exhaust stroke, and the piston on the right at an intermediate point in the suction stroke.

In Fig. 5 the piston on the left is at an intermediate point in the exhaust stroke and the piston at the right is starting on the compression stroke.

10 In Fig. 6 the piston on the left is starting on the suction stroke and the piston on the right is at an intermediate point in the compression stroke.

15 In Fig. 7 the left hand piston is at an intermediate point in the suction stroke and the right hand piston is starting on its power stroke.

20 In Fig. 8 the left hand piston is shown as starting on the compression stroke and the right hand piston is at an intermediate point in the power stroke.

25 In Fig. 9 the left hand piston is at an intermediate point in the compression stroke and the right hand piston is starting on the exhaust stroke.

30 It is evident from careful inspection of the diagrams that if the valve crank shaft is operated at half the speed of the engine crank shaft, the valves although they are coupled to the same wrist pin, are always in the proper position. Furthermore, the valve mechanism, including the valve crank shaft, utilizes the space between the engine cylinders and produces in consequence a 35 very compact and desirable arrangement. Furthermore, since each valve cylinder is at an angle to the engine cylinder with which it co-operates, they open into the combustion chamber very close together, thereby making 40 it possible to use a smaller combustion chamber and increasing the efficiency of the engine.

45 The piston valves also serve to deliver power through the gearing to the engine shaft.

50 The angle between the center lines of the opposite valve cylinders is determined by the angle between the center lines of the engine cylinders; for example, when the engine cylinders have a 90 degree relation the valve cylinders will have a substantially 135 degree relation.

55 My invention is particularly applicable to engines for automobiles, aeroplanes and motor boat service, but is not limited to any particular field of usefulness. Furthermore, the structure shown and described is intended to be illustrative of only one embodiment of my invention, and I intend that 60 only such limitations be imposed as are indicated in the appended claims.

What I claim is:

1. An internal combustion engine comprising a crank-shaft, a pair of cylinders at 65 an angle to each other, pistons operating in

the cylinders and eccentrically connected with said crank-shaft at a common axis of eccentricity, a valve for each of said cylinders, a valve-operating shaft within the angle of the cylinders, said valve-operating shaft having an eccentric thereon, means for connecting the valve-operating shaft to turn at one-half the speed of the crank-shaft, operating means for said valves comprising pivotal connections, a connecting rod between each of said pivotal connections and a common point on said eccentric, and means for guiding the motion of said pivotal connections at an angle to each other and each at an angle to the axis of its respective cylinder, to thereby obtain the proper relative time of movement of both of the valves from said common eccentric.

2. An internal combustion engine comprising a crank-shaft, a pair of cylinders at 85 an angle of substantially 90 degrees to each other, pistons operating in the cylinder and eccentrically connected with said crank-shaft at a common axis of eccentricity, a valve for each of said cylinders, a valve-operating shaft within the angle of the cylinders, said valve-operating shaft having an eccentric thereon, means for connecting the valve-operating shaft to turn at one-half the speed of the crank-shaft, operating means 90 for said valves comprising pivotal connections, a connecting rod between each of said pivotal connections and a common point of said eccentric, and means for guiding the motion of said pivotal connections at an angle of substantially 135 degrees to each other, to thereby obtain the proper relative time of movement of the valves from said eccentric.

3. An internal combustion engine comprising a crank shaft, a pair of cylinders at an angle to each other, pistons operating in the cylinders and eccentrically connected with said crank shaft at a common axis of eccentricity, a valve for each of said cylinders, a valve operating shaft, means for connecting the valve operating shaft to turn at one-half the speed of the crank shaft, operating means for said valves comprising pivotal connections, connecting rods between 105 said pivotal connections and a common point of eccentricity of said valve operating shaft, and means for guiding the motions of said pivotal connections at an angle to each other and each at an angle to the axis of its 110 respective cylinder to thereby obtain the proper relative time of movement of both of the valves from said common eccentric.

4. An internal combustion engine comprising a pair of engine cylinders having 125 their axes at an angle to each other, pistons operating in the cylinders, a crank-shaft having a single wrist pin to which both pistons are operatively connected, valve cylinders each at an angle to the engine cylinder 130

- with which it coöperates, a valve crank shaft operatively connected to the engine shaft and piston valves in the valve cylinders eccentrically connected to the valve crank shaft at a common axis of eccentricity.
5. An internal combustion engine comprising a pair of engine cylinders having their axes at an angle to each other, pistons operating in the cylinders, a crank-shaft 10 having a single wrist pin to which both pistons are operatively connected, valve cylinders each at an angle to the engine cylinder with which it coöperates, piston valves each at an angle to the cylinder with which it is associated, a valve crank shaft connected to operate at one-half the speed of the crank shaft and having a single wrist pin to which the valves are connected at a common axis of eccentricity.
- 15 6. An internal combustion engine comprising a crank shaft, a pair of cylinders at an angle to each other, pistons operating in the cylinders and eccentrically connected to said crank shaft at a common axis of eccentricity, a valve cylinder for each of said cylinders and disposed at an angle thereto, a piston valve operating in each valve cylinder, a valve operating shaft within the angle of the cylinders, means for connecting the 20 valve operating shaft to turn at one-half the speed of the crank shaft, means for connecting the piston valves in the respective valve cylinders to said valve operating shaft at a common axis of eccentricity, the timing of 25 the valves being determined by the angles

between centers of the piston valves relative to the engine pistons.

7. An internal combustion engine comprising a pair of engine cylinders having a substantially 90 degree relation between 40 their axes, valve cylinders respectively associated with the engine cylinders and having a substantially 135 degree relation, pistons in the engine cylinders, a crank-shaft having a single wrist pin to which both pistons are connected at a common axis of eccentricity, piston valves, and a valve crank shaft having a single wrist pin to which the piston valves are connected, said valve crank shaft being connected to operate at a slower speed 45 than the crank shaft.

8. An internal combustion engine comprising a crank shaft, a pair of cylinders at an angle to each other, pistons operating in the cylinders and eccentrically connected 50 with said crank shaft at a common axis of eccentricity, and valve cylinders coöperating with the respective engine cylinders with their center lines at a greater angle to each other than the angle existing between the 55 engine cylinders; piston valves in the valve cylinders, a valve operating shaft connected to be turned at a slower speed than the crank shaft, and means for eccentrically connecting the piston valves to the valve operating 60 shaft at a common axis of eccentricity.

In witness whereof, I have hereunto set my hand this 3 day of September, 1915.

ALDEN E. OSBORN.
